UNITED STATES PATENT OFFICE.

AUSTIN EDWIN GREENE, OF MEDFORD HILLSIDE, MASSACHUSETTS, ASSIGNOR, BY MESNE ASSIGNMENTS, TO CONDIT ELECTRICAL MANUFACTURING COMPANY, A CORPORATION OF MASSACHUSETTS.

CIRCUIT INTERRUPTER.

Application filed July 10, 1922. Serial No. 573,803.

To all whom it may concern:

Be it known that I, AUSTIN EDWIN GREENE, a citizen of the United States, residing at Medford Hillside, in the county 5 of Middlesex and State of Massachusetts, have invented an Improvement in Circuit Interrupters, of which the following is a specification.

This invention relates to electric switches, 10 and especially oil immersed electric switches, of relatively high capacity.

When a circuit carrying a relatively heavy load is interrupted under oil, or other arc quenching medium, the oil is thrown 15 violently about within the oil receptacle of the switch due to the gases evolved at the arc, and some of the oil may be, and usually is, expelled from the switch.

An object of this invention is to provide 20 a switch with a vent to the atmosphere and means interposed between the oil chamber of the switch and the vent to catch the oil which would otherwise pass through the vent and return it to the oil chamber.

25 The gaseous pressure set up within the switch by the circuit interrupting arc may be relatively great and a further object is to provide yielding means connecting the oil receptacle and its cover whereby to 30 momentarily increase the expansion space above the oil in the switch and keep down the pressure rise, and absorb energy resulting from such increase of pressure, and also to reduce the strain on the means connecting the oil receptacle and cover.

35 My invention may be embodied in a type of switch characterized by having main contact members carried externally by the switch casing and adapted to carry the current, and auxiliary contact members disposed within the casing under the oil therein adapted to interrupt the circuit.

It is a further object of my invention to provide a switch of this type with a relatively yielding casing and cover and oil catching means and main contact members carried by the fixed oil receptacle of the switch.

With my invention, I am enabled materially to reduce the manufacturing expense of the switch.

A further object is generally to improve the construction and operation of electric switches.

Fig. 1 is a front elevation, partly in section, of an electric switch embodying my invention. 55

Fig. 2 is a plan view of the switch of Fig. 1.

Fig. 3 is a sectional detail of a modified 60 form of oil receptacle and oil separator elements.

Fig. 4 is a sectional elevation of a modified 65 form of switch casing embodying my invention.

Fig. 5 is a plan view of the oil separator element of Fig. 4.

Figs. 6 and 7 are sectional elevations of 70 switch casings similar to that of Fig. 4 and illustrating further modified forms of oil separator elements.

Fig. 8 is a sectional elevation of a switch 75 wherein the cover is fixed in position and the oil receptacle is yieldingly supported.

Fig. 9 is a detailed sectional elevation of 80 a dash pot of the switch of Fig. 8.

In Fig. 1, I have illustrated the invention applied to the specific type of switch characterized by having main contact members arranged externally of the switch and auxiliary contact members disposed in the oil in the oil receptacle of the switch. Fig. 1 illustrates a two pole switching unit with the poles arranged in series. Both poles are similar and but one will be described. 85 The switch includes the cylindrical metal oil receptacle or pot 10 which comprises a terminal of the switch and the cover 11 which preferably, although not necessarily, is formed of metal, for strength. The cover 90 is formed with a central aperture and an insulating bushing 12 is extended through the aperture and secured to the cover, and the bushing is adapted to receive and guide the movements of an auxiliary movable contact member. The oil receptacle 10 is received in a boss 13 of a plate 14, and is electrically connected therewith. Said plate 95 is supported on top of an insulating bushing 15 which is secured to a fixed, and preferably insulating, support 16, and said plate is or may be fixed in position by the bolt 17 which is threaded in the plate and extended through the bushing. Said bolt may comprise the terminal member of the switch.

100 A ring 18 is or may be received about and fixed to said oil receptacle intermediate the ends thereof, and preferably at the upper 105

portion thereof. Said ring forms means by which the oil receptacle is secured to said plate 14 and tie rods 19 may extend through an outstanding flange 20 of said ring and 5 through said plate 14, and firmly connect said ring and plate, whereby rigidly to secure the receptacle to the plate and support the receptacle in upright position.

Said oil receptacle is or may be provided 10 with a bottom recess in which an auxiliary stationary contact member 21 is received and electrically connected to the receptacle.

In accordance with my invention, I secure the main contact member 22 to the 15 outer face and at the upper part of the oil receptacle and said contact member is consequently held in fixed position by the oil receptacle. Said contact member is or may be provided with wedge-shaped contact faces 20 and is extended laterally beyond the cover 11, as shown, for engagement with a suitable main movable contact member.

The movable contact members are or may be secured to and carried by an electrically- 25 conducting bar 25 disposed above the oil receptacles and fixed to a vertically extended rod 26 depending from suitable switch-operating mechanism, not shown. The auxiliary movable contact member comprises a rod 27 30 secured to and depending from an end of said bar 25 and slidably extended through said insulating bushing 12 into the oil receptacle and adapted to make and break contact with the auxiliary stationary contact member 21 in said receptacle. The main movable contact member may comprise a plurality of spring fingers 28 secured to and depending from an intermediate portion of said bar 25 and adapted to engage the main 35 stationary contact members 22.

The arrangement of the main and auxiliary contact members is such that the auxiliary contact members are adapted to separate last, whereby to interrupt the circuit under 40 oil.

Oil or other equivalent arc-quenching medium is adapted to be contained in the oil receptacle to some suitable level *a—a* and the 45 space B above the oil and under the cover comprises an expansion space or chamber for the gas and vapor resulting from circuit interruption.

In accordance with my invention, the oil 50 receptacle and cover comprising the switch casing are made relatively yielding and, for this purpose, the oil receptacle is held fixed in position and the cover is arranged to be 55 yieldingly supported on the oil receptacle. The yielding supporting means may include 60 the rods 30 which may be secured to that portion of the cover extended laterally beyond the receptacle and said rods depend downwardly over the side wall of the receptacle. Said rods may pass slidably 65 through apertures in the flange 20 of the

ring 18 carried by the oil receptacle and compression springs 31 may encircle the lower ends of said rods and engage the lower face of said flange and nuts 32 threaded adjustably on the lower ends of said rods. It is 70 obvious that when a gaseous pressure exists within the gas expansion space B of the oil receptacle greater than the springs 31 can resist, the cover will move upwardly away from the oil receptacle and relieve such pressure. The effect of said springs 31 may be varied by varying the position of the nuts 32 on the rods 30.

Preferably said cover is adapted normally to rest upon the top of the oil receptacle and, if the cover and receptacle are machined to form a good seat, the casing will be practically sealed until the gas pressure within the switch is sufficient to raise the cover and permit the gas to escape to the atmosphere over 85 the top of the oil receptacle. Ordinarily, however, there may be a restricted vent passage between the cover and the top of the receptacle through which the switch may breathe. 90

The gas and vapor expelled from the switch during circuit interruption may be highly heated and partially electrically conducting; consequently, means are or may be provided to direct such gas and vapor downwardly and away from the movable contact members. Said means may comprise a depending annular flange or apron 11^a which may be integrally formed with the cover 11 and enclose the top portion of the oil receptacle and depend downwardly over the side thereof a distance to guide downwardly gas and vapor expelled from the switch. Preferably, said flange is peripherally spaced from the side wall of the oil receptacle to provide a 100 narrow channel 33 down which the heated gas may pass, and the cooling effect of the cool walls of the flange and receptacle may materially reduce the temperature of the gas 105 as it is discharged into the atmosphere. 110

It is an object of this invention to provide means to separate oil which would otherwise be expelled from the switch and return it to the main body of oil in the oil receptacle and said means, preferably, is contained within the switch casing. In Fig. 1, the separating means may include the cylindrically-shaped element 35 which is received within the upper portion of the oil receptacle and spaced from the side wall thereof to provide an annular chamber or compartment C in which the oil separated from the gas stream passing toward the vent is deposited to be returned to the main body 115 of oil in the receptacle. 120

Said separator element extends upwardly toward the cover 11 and may terminate adjacent the lower face of the cover to provide an annular passage 36 of relatively 125 small height over the top of the element 126

and under the cover through which the combined stream of gas and oil is adapted to pass, or said passage may be otherwise formed. Said cover is or may be formed with an annular depending flange or apron 11^b adapted to surround the upper portion of said separator element and depend below the annular passage 36 and downwardly over the side wall thereof and into the annular compartment C and, preferably, said flange is spaced from the separator element to provide a narrow annular passage 37 down which gas and oil are guided into said compartment C. Hot gas and oil may be cooled, and oil vapor may be condensed by contact with the relatively cool flange 11^b and the wall of the separator element. Preferably, said flange 11^b has such downward extent that it serves to direct downwardly into the compartment C the gas stream passing from the gas expansion chamber B when the cover is moved upward by the gas pressure within said chamber B.

Said separator element preferably extends below the surface of oil in the oil receptacle and may be arranged to provide communication between the compartment C and the oil space in the receptacle, whereby to provide for the return to the main body of oil of the oil separated from the gas stream and collected in the compartment C. For this purpose, said separator element may be formed or provided with the outwardly extended annular wall 38 which may form the bottom wall of said compartment C, and said wall may be formed with the apertures 39 therein which, preferably, are disposed below the level of the oil in the receptacle. Said separator element may also be formed or provided with the lower cylindrical wall 41 adapted to be supported removably or be fixed to the wall of the oil receptacle in a suitable manner.

As thus arranged, oil may be in the compartments B and C to the same level and preferably above the apertures 39, and said compartments may be in gaseous communication only by means of the passages 36 and 37 and have the same pressure conditions, and be normally at atmospheric pressure. When the movable contact members are moved upwardly and an arc is drawn between the auxiliary contact members in the oil receptacle a considerable amount of gas and oil vapor may be generated, due to the heat of the arc, and oil may be expelled violently upward. The increase in gaseous pressure may effect the yielding and consequent upward movement of the cover 11 against the action of the springs 31. The stream of combined gas and oil, some of which may be in the form of oil vapor, may pass through the passage 36 and downward through the passage 37 into the annular compartment C. Oil may be separated from

the gas in said compartment and the substantially oil free gas may pass between the oil receptacle and the cover into the passage 33 and downwardly into the atmosphere. The arrangement of the apparatus may be very effective in separating the oil from the gas stream. The gas stream passes downwardly in the passage 37 and abruptly over the lower edge of the flange 11^b and thence upwardly. As the gas stream passes over the lower edge of said flange it is given an abrupt change in direction of motion and oil contained in the gas stream, being heavier than the gas, is projected downwardly out of the gas stream at this point, due to centrifugal action, and into the relatively motionless or dead gas space in the compartment C, and is collected in said compartment and returned to the main body of oil in the receptacle. Oil vapor condensed in the passage 37 is also collected in the compartment C and but relatively oil-free gas is discharged from the switch. It is preferable that the gas stream be guided to make an abrupt turn over the dead gas space in said compartment rather than to pass more or less horizontally through the upper portion of the compartment as the latter arrangement may not be so effective to separate oil, and especially the more finely divided particles of oil, from the gas stream.

It is also preferable that the communicating passage between the compartment C and the main oil chamber of the switch be beneath the surface of the oil, rather than above the surface, as, with the latter arrangement, gas may pass through said passage and pick up and carry out of the switch, oil that may be separated from the gas stream in the upper part of said compartment. When oil covers the communicating passage, the oil catching compartment will be sealed so far as passage of gas through said passage is concerned.

In the modification illustrated in Fig. 3, the upper portion of the oil receptacle is formed with the reduced neck-portion 10^a and a tubular member 35^a is secured to the receptacle about the neck whereby to form the annular compartment C. This construction is identical in function with that illustrated in Fig. 1.

The invention is also applicable to switches having oil receptacles of other than cylindrical formation. Fig. 4 illustrates a switch having the fixed-switch frame 45 which forms a cover for the rectangular oil receptacle 46, and said receptacle may be secured to and depend yieldingly from the cover by means of the bolts 47 and springs 48. Said cover may be formed with a depending peripheral flange or apron 45^a adapted to be received within the oil receptacle. A separator element 49 of substantially rectan-

gular formation may be received within said oil receptacle and may rest upon the insulating lining 50 disposed within the lower portion of the receptacle. Said 5 separator element may have its upper end disposed within said flange 45^a and be arranged and function in the manner set forth in connection with Fig. 1.

In Fig. 7, the separator element comprises 10 a rectangular shell 55 secured by bolts 56 to and in spaced relation with the wall of the oil receptacle and the passage 57 between said shell and the oil receptacle, or the lining 50^a thereof, provides fluid communication between the annular compartment C and the main body of oil in the receptacle.

I may support the separator element by 15 the cover instead of the oil receptacle and Fig. 6 illustrates such an arrangement. The separator element may comprise a rectangular shell 60 similar to the element 35 of Fig. 7 and may be secured to and spaced from the flange 61^a of the cover 61 by bolts 20 62 and depend toward and terminate preferably below the surface of oil in the oil receptacle.

It is not essential that the compartment 25 C be placed in communication with the oil compartment of the switch and Fig. 8 illustrates an arrangement wherein the compartment C', which is equivalent of the compartment C of Fig. 1 is sealed from liquid communication with the oil space of the

30 oil receptacle. For this purpose, an annular member 65 may be disposed about and spaced from the upper portion of the cylindrical oil receptacle 66, and the lower wall 67 of said annular member may be 35 fixed in fluid tight engagement with the wall of the oil receptacle as by welding it thereto. The annular compartment C' is adapted to be relatively deep whereby to contain a substantial amount of oil, which 40 oil may be expelled from the interior of the switch in successive switching operations.

Said oil receptacle 66 may be secured 45 yieldingly to the fixed cover 68 by means of the rods 69 which are or may be secured to said cover and extend slidably through apertures in the ring 70 secured to the receptacle. Springs 71 may encircle the lower ends of said rods and bear against abutments 72 of said rods and the lower face of 50 said ring whereby to force the oil receptacle yieldingly against the cover.

Means may be provided to retard the upward movement of the oil receptacle and 55 said means may include the dash pots 75 secured in fluid tight engagement with and depending from the ring 70 of the oil receptacle and enclosing the lower ends of said rods 69 and the springs thereon. Pistons 76 may be slidably received on the 60 ends of said rods between the upper abut-

ments 72 and lower stop-pins 77 and arranged to control passages 78 in said rods which are arranged to establish fluid communication between the portions of the dash pots disposed on opposite sides of said 70 pistons. Said dash pots may be filled with oil or other suitable fluid.

When the oil receptacle moves downwardly from its cover in response to gaseous 75 pressure conditions within the switch, said dash pots are carried downwardly with the oil receptacle, and the pressure of the oil on the upper side of the piston 76 moves said pistons downwardly on the rods 69 to uncover the passages 78 whereby to permit substantially free fluid communication between the upper and lower portions of said dash pots and consequently the substantially unrestricted downward movement of the oil receptacle. When said receptacle subsequently begins to move upward under the action of the springs 71, said pistons 76 are moved upwardly under fluid pressure to close said passages 78. The rate of upward movement of said receptacle is then governed by the rate of fluid leakages between the edge of the pistons and the walls of the dash pots, or equivalent leak passages, and the oil receptacle may be returned gradually and without shock to its normal 85 position beneath the cover thereof.

The construction herein shown may be modified without departing from the spirit of the invention.

I claim:

1. An oil receptacle for an electric switch constructed and arranged to provide a lower oil-containing compartment and an upper oil-catching compartment both arranged for intercommunication at the upper portions thereof, said oil-catching compartment having a bottom normally sealed against passage of gas therethrough.

2. An electric switch having an oil receptacle constructed and arranged to provide a lower oil-containing compartment and an upper oil-catching compartment both arranged for intercommunication at the upper portions thereof, said oil-catching compartment having a normally sealed bottom, and a single cover for both compartments.

3. An oil receptacle for an electric switch constructed and arranged to provide a single-walled lower portion and a double-walled upper portion with the walls thereof constructed and spaced to provide an upper oil catching compartment normally sealed against gas entrance at the bottom and having a gas entrance at the top.

4. An oil receptacle for an electric switch constructed and arranged to provide a single-walled lower portion and a double-walled upper portion with the walls thereof constructed and spaced to provide an upper

oil-catching compartment normally sealed against gas entrance at the bottom and having a gas entrance at the top, said compartment disposed mainly above the oil level 5 in the receptacle.

5. An oil receptacle for an electric switch having a compartment disposed within the side walls of and located mainly above the oil level in the receptacle, said compartment 10 having its bottom normally sealed against gas entrance and having an open top by which gas can enter the compartment.

6. An oil receptacle for an electric switch having a member carried by and secured to 15 and spaced from the upper portion thereof and constructed and arranged to provide an upper peripheral oil-catching compartment normally sealed against gas entrance thereto at the bottom and open for gas entrance at 20 the top.

7. An oil receptacle for an electric switch constructed and arranged to provide an oil-containing compartment and an oil-catching compartment disposed mainly above the oil 25 level in the oil-containing compartment and open at the top and in communication at the bottom with said oil-containing compartment beneath the oil level therein.

8. An oil receptacle for an electric switch 30 constructed and arranged to provide an oil-containing compartment and a peripheral oil-catching compartment disposed mainly above the oil level in the oil-containing compartment and open at the top and in communication at the bottom with said oil-containing compartment beneath the oil level therein.

9. An electric switch including a cover 40 and an oil receptacle disposed beneath said cover constructed and arranged to provide a compartment adapted to contain oil and the switch members, and an oil-catching compartment disposed mainly above the oil level in the oil-containing compartment and having a normally sealed bottom, said compartments arranged for intercommunication 45 above the oil level and under the cover.

10. An electric switch including a cover 50 and an oil receptacle disposed beneath said cover constructed and arranged to provide a lower compartment adapted to contain oil and the switch members, and an upper oil-catching compartment arranged for communication with said first compartment at the top and at the bottom beneath the oil level in said receptacle.

11. An electric switch having a cover, 60 and an oil receptacle disposed beneath said cover, said oil receptacle having an oil-containing compartment and an oil-catching compartment disposed mainly above the oil level in said oil-containing compartment and arranged for gaseous communication with said lower compartment at its top under the cover, and for oil communication at

its bottom, the oil in the receptacle adapted to fill both compartments normally to the same level.

12. An electric switch having upper and lower compartments, said lower compartment arranged to contain oil and the switch members and vent into the upper compartment, said upper compartment arranged to vent into the atmosphere and having a passage at the bottom in communication with said lower compartment below the oil level therein. 70

13. An electric switch having two compartments, said first compartment arranged to contain oil and the switch members and vent into the second compartment, said second compartment arranged to vent into the atmosphere, and having a passage at the bottom in communication with said first compartment below the oil level therein, and 80 a cover for both compartments arranged to move upwardly due to gaseous pressure within the switch. 85

14. An electric switch comprising an oil receptacle and a cover therefor, and a member disposed within the upper portion of the receptacle and spaced from the side wall thereof arranged to provide an inner peripheral compartment which is arranged for fluid communication with the oil space 90 in the receptacle below the oil level therein. 95

15. An electric switch comprising an oil receptacle and a cover therefor, and a member disposed within the upper portion of the receptacle and spaced from the side wall of the receptacle to provide a peripheral compartment extended downwardly below the oil level in the receptacle, said member and cover cooperating to provide a communicating passage between the oil receptacle and said compartment. 100 105

16. An electric switch comprising an oil receptacle and a cover therefor, and a member disposed within the upper portion of the receptacle and spaced from the side wall of the receptacle to provide a peripheral compartment extended downwardly below the oil level in the receptacle, and having oil communication with the oil in said receptacle below the oil level therein and gaseous communication with said receptacle at the top of said peripheral compartment. 110 115

17. An electric switch having an oil receptacle, a member received in the upper portion of said oil receptacle and having a side wall spaced from the side wall of the receptacle to provide a peripheral compartment, said member extended downwardly below the oil level in the receptacle and having an outstanding bottom wall carried by the receptacle which has an aperture therein submerged in the oil in the receptacle. 120

18. An electric switch having an oil receptacle, a member received in the upper portion of said oil receptacle and having a side 125 130

wall spaced from the side wall of the receptacle to provide a peripheral compartment, said member extended downwardly below the oil level in the receptacle and having an outstanding bottom wall carried by the receptacle which has an aperture therein in the oil in the receptacle, and a cover for said receptacle and compartment, said compartment and oil receptacle arranged for gaseous intercommunication at the top under the cover.

19. An electric switch having the combination of a fixed oil receptacle, a yieldingly supported cover for said receptacle, a main fixed contact member carried by said receptacle, a fixed auxiliary contact member disposed beneath the oil in said receptacle, and movable main and auxiliary contact members cooperating with said fixed contact members.

20. An electric switch having the combination of a fixed oil receptacle, a yieldingly supported cover for said receptacle, a fixed main contact member carried externally by said oil receptacle, a fixed auxiliary contact member disposed beneath the oil in said receptacle and movable main and auxiliary contact members cooperating with said fixed contact members.

21. An electric switch having the combination of a fixed oil receptacle adapted to form one terminal of the switch, a cover for said receptacle, means yieldingly connecting said cover and receptacle, a fixed main contact member carried externally by said oil receptacle, a fixed auxiliary contact member disposed beneath the oil in said oil receptacle, a movable main contact member cooperating with said fixed main contact member, and a movable auxiliary contact member extended through said yieldingly supported cover for cooperation with said fixed auxiliary contact member.

22. An electric switch comprising the combination of a fixed oil receptacle forming a terminal of the switch and having an oil-catching compartment in communication with the interior of said receptacle and also with the atmosphere, a cover for said receptacle and compartment, a fixed external main contact member carried by the oil receptacle, a fixed auxiliary contact member disposed beneath the oil in the oil receptacle, and movable main and auxiliary contact members cooperating with said fixed contact members.

23. An electric switch comprising the combination of a fixed oil receptacle forming a terminal of the switch and having an oil-catching compartment, a cover for said receptacle and compartment, means yieldingly supporting said cover in position, a fixed external main contact member connected with the oil receptacle, a fixed aux-

iliary contact member disposed beneath the oil in the oil receptacle, and movable main and auxiliary contact members cooperating with said fixed contact members.

24. An electric switch comprising the combination of a fixed oil receptacle forming a terminal of the switch and having an oil-catching compartment, a cover for said receptacle and compartment having a flange depending into said compartment, a fixed external main contact member connected with the oil receptacle, a fixed auxiliary contact member disposed beneath the oil in the oil receptacle, and movable main and auxiliary contact members cooperating with said fixed contact members.

25. An electric switch comprising the combination of a fixed oil receptacle forming a terminal of the switch and having an oil-catching compartment, a cover for said receptacle and compartment having a flange depending into said compartment, means yieldingly supporting said cover in position, a fixed external main contact member connected with the oil receptacle, a fixed auxiliary contact member disposed beneath the oil in the oil receptacle, and movable main and auxiliary contact members cooperating with said fixed contact members.

26. An electric switch comprising the combination of a fixed oil receptacle forming a terminal of the switch and having an oil-catching compartment, a cover for said receptacle and compartment, said switch arranged to vent into said compartment and thence into the atmosphere, said cover having a flange depending into and spaced from the walls of said compartment, a fixed external main contact member carried by said oil receptacle, a fixed auxiliary contact member disposed beneath the oil in the oil receptacle, and movable main and auxiliary contact members cooperating with said fixed contact members.

27. An electric switch comprising the combination of a fixed oil receptacle forming a terminal of the switch and having an oil-catching compartment, a cover for said receptacle and compartment, said switch arranged to vent into said compartment and thence into the atmosphere, said cover having a flange depending into and spaced from the walls of said compartment, means yieldingly supporting said cover in position, a fixed external main contact member carried by said oil receptacle, a fixed auxiliary contact member disposed beneath the oil in the oil receptacle, and movable main and auxiliary contact members cooperating with said fixed contact members.

In testimony whereof I have signed my name to this specification.

AUSTIN EDWIN GREENE.
